UNITED STATES PATENT OFFICE.

LOUIS FLORY AND KAROL KLEINO, OF PHILADELPHIA, PENNSYLVANIA.

AUTOMATIC GATE FOR RAILWAY CROSSINGS.

Application filed May 20, 1926. Serial No. 110,331.

Our invention relates to a new and useful automatic gate for railway crossings and the like, and it relates more particularly to a novel system for operating gates for railway crossings, whereby a positive, unfailing and dependable operation of the gates may be obtained at all times, properly timed with relation to the travel of a train past the crossing.

10 Our invention further relates to a novel construction in a railway crossing gate, and a novel system for operating the same, whereby the gates are closed and opened or lowered and raised, by entirely mechanical means, actuated by the train itself, and whereby the possibility of any accidents due to the closing of the gates upon a vehicle crossing the railway, is entirely eliminated by the provision of novel yieldable gate

20 arms. With the above ends in view, our invention consists of suitable gate posts on either side of the track, gate arms pivotally mounted at their upper ends, lifting tracks slidably mounted in said gate posts and operatively engaging said gate arms, pinions carried by said posts in mesh with said lifting rack adapted to raise and lower the same, thereby to raise and lower the gate arms, 25 said pinions being carried by horizontal operating shafts extending transversely across the tracks and beneath the upper surfaces of the same, pinions carried by said horizontal shafts beneath and intermediate the 30 tracks, an operating rack extending parallel to the tracks and positioned below the upper surfaces thereof, in mesh with said second pinions, adapted to rotate the same, a plurality of actuating racks positioned along 35 the tracks at suitable distances on either side of the crossing connected with the main operating racks by suitable rods or cables, actuating pinions in mesh with said actuating racks and tripping levers carried by said 40 pinions extending above the upper surface of the tracks and positioned in operative alignment with the flange of the locomotive wheel tire, whereby the engagement of the flange of the tire of the locomotive with the 45 tripping lever will deflect the same and displace said series of actuating racks and said main operating racks, thereby to lower or raise the gate arms.

50 For the purpose of illustrating our invention, we have shown in the accompanying drawings, forms thereof which are at

present preferred by us, since they will give in practice satisfactory and reliable results, although it is to be understood that the various instrumentalities of which our invention consists can be variously arranged and organized and that our invention is not limited to the precise arrangement and organization of these instrumentalities as herein shown and described.

55 Figure 1 represents a diagrammatic view in elevation, of the railway crossing gate and actuating system therefor, embodying our invention.

60 Figure 2 represents a diagrammatic top plan view of the same.

65 Figure 3 represents a section on line 3—3 of Figure 2, on an enlarged scale, showing one of the tripping levers and actuating devices.

70 Figure 4 represents a top plan view of the actuating device and tripping lever shown in Figure 3.

75 Figure 5 represents a section on line 5—5 of Figure 3, on an enlarged scale, showing one of the rod or cable guides.

80 Figure 6 represents a horizontal section on line 6—6 of Figure 1, showing the main operating shaft.

85 Figure 7 represents a vertical section of one of the gate posts, showing the yieldable gate arm construction.

90 Figure 8 represents a section on line 8—8 of Figure 7, showing the universal pivot head of the yieldable gate arm construction.

95 Figure 9 represents a top plan view of the gate arm and post, shown in Figure 7.

100 Referring to the drawings, in which like reference characters indicate like parts, 1 and 2 designate a pair of upright gate posts on one side of the tracks and at a suitable distance from the rails, while 3 and 4 designate a corresponding pair of gate posts on the other side of the track, also at a suitable distance from the other side of the rails. Each of the gate posts 1, 2, 3 and 4, carry a pair of T shaped pivot plates 5 and 6, pivotally secured on either side of the post by means of the pivot pins 7. To the lower ends of the pivot plates 5 and 7 is pivotally secured a rod connector or terminal member 8, by means of the pivot pin 9 in which the upper terminal of the lifting rod 10 is secured. The lifting rod 10 in turn telescopes into the inner bore 11 of a suitable upright lifting rack 12, which is held in mesh with the lifting pinion 13 carried by the hori-

zontal main operating shaft 14, and is carried by the rack guide 15. A helical compressing spring 16 is interposed between the rod connector 8 and the upper end of the lifting rack 12, thereby yieldably to transmit the vertical movement of the lifting rack 12 to the pivot plates 5 and 6. Thus by revolving the horizontal main or operating shaft 14, and hence the pinion 13, the lifting rack 12 is moved vertically and hence the pivot plates 5 and 6 are deflected.

The universal swivel members 17 are pivotally mounted and secured between the free ends of the pivot plates 5 and 6, by means of the nuts 18. By this means the universal swivel member 17 is capable of oscillating movement about the horizontal trunnions 19 thereof. The gate arms 20, having the forked and pivotal ends 21 are in turn pivotally mounted on the vertical trunnions 22 of the swivel members 17 and are secured thereto by means of the nuts 23. A pair of flat springs 24 may be secured to the pivot plates 5 and 6, by means of the nuts 18, thereby yieldably to maintain the pivoted gate arms 20 in median or neutral positions, as shown in Figures 7 and 9.

By this double pivotal mounting of the gate arms 20, the pivot plates 5 and 6, may be lowered into the lower or closed position, without positively lowering the gate arm 20, since the same may be deflected with respect to the pivot plates and thus maintained in an upper position. If the gate is thus closed down upon a vehicle passing beneath it, the gate arm will not prevent the passage of the vehicle, and will allow the same to clear the gate. Similarly, due to the horizontal pivotal and yieldable mounting of the gate arms 20, and the yieldable mounting thereof between the two springs 24, a vehicle may encounter the gate arms 20 without serious damage, since the same will be deflected and spring back into the normal or closed position after the vehicle has passed. This is particularly advantageous, as it eliminates any possibility of the vehicle being caught between the two gates on the two sides of the track respectively, since it will require but little force to deflect the gate arms.

Each of the horizontal main or operating shafts 14, extends transversely across the tracks at a level slightly below the upper surface of the rails, and interconnects the corresponding pinions 13 in the gate posts 1 and 3, and 2 and 4 respectively.

The automatic tripping or actuating mechanism shown particularly in Figures 1, 2, 3 and 4, is composed of a main rack bar 26, slidably mounted in the two guides 27 and 28 adjacent and parallel to one of the rails 29, shown particularly in Figure 2, which is provided with an upper rack 30 and a lower rack 31, near the two ends thereof respectively. Each of the horizontal main

or operating shafts 14, carries a pinion 32 in mesh with the racks 30 and 31 respectively, whereby said shafts 14 are both revolved simultaneously and in opposite directions by the displacement of the rack bar 26. Thus upon moving the rack bar 26 in the direction of the arrow 33, the shafts 14 are revolved so as to lower the gate arms 20, while upon moving the rack bar 26 in the direction of the arrow 34, the gate arms 20 are raised. 70 75

In order automatically to actuate the rack bar 26 in synchronism with the movement of a train, and in order to actuate said rack bar 26 successively in the two directions indicated by the two arrows 33 and 34 respectively, thereby to lower and raise the gate arms 20 with the approach and passage of the train respectively, one or several train operated tripping or actuating devices are provided along the track adjacent to one of the rails, and at suitable distances in advance of and past the gate or crossing.

Thus, assuming a train to travel in the direction of the arrow 33, two train operated gate actuating devices 36 and 37 are provided in advance of the gates or crossing and two train operated gate actuating devices 38 and 39 are provided past the crossing or gates. Thus, a tripping or actuating device 36 may be placed about a mile in advance of the gates or crossing, while the second tripping or actuating device may be placed three quarters of a mile in advance. The actuating or resetting devices 38 and 39 may be placed short distances from the gates or crossing, that is, about one fourth and one third of a mile respectively, along the track. Each of the actuating devices 36, 37, 38 and 39, as shown in Figures 3 and 4, is composed of a horizontal actuating rack 40, 41, 42 and 43 respectively, slidably mounted in suitable housings 44, 45, 46 and 47 respectively, and rotatably mounted actuating pinions 48, 49, 50 and 51 respectively, in mesh with the corresponding actuating rack, carried by suitable shafts or studs 52. The shafts or studs 52 carry suitable actuating tripping or setting levers or arms 53, 54, 55 and 56 respectively. 90 95 100 105 110 115

The actuating racks 40, 41, 42 and 43 and the main rack bar 26 are connected in series by suitable rods 57, 58, 59 and 60, which are suitably supported and guided by spring pressed guide rolls 61, carried in suitable housings 62, at suitable intervals along the track. Thus a displacement of any one of the actuating racks 40, 41, 42 and 43, displaces every other actuating rack, as well as the main rack bar 26.

Each of the actuating, tripping or setting levers or arms 53, 54, 55 and 56, disposed directly adjacent to the inner side of one of the rails 29, so as to be in operative alignment with the flanges of the wheel. The actuating levers or arms are, moreover, dis- 125 130

posed in angularly spaced relation to each other, so that the first two actuating levers or arms 53 and 54 are approximately 45 degrees apart as shown in Figure 1, with the arm 53 inclined forwardly at an angle of 45 degrees while the arm 54 is in an upright position, with the gate arms 20 in the open position. Similarly, the arms 55 and 56 are also approximately at an angle of 45 degrees to each other, with the arm 55

10 inclined downwardly at an angle of 45 degrees, while the arm 56 is in the horizontal position with the gate arms 20 in the opened position, as indicated in Figure 1.

15 By this novel actuating system, a train approaching from the right, (Figure 1) in the direction of the arrow 34, first encounters the actuating or tripping lever or arm 53, and deflects it to the horizontal position,

20 that is, about 45 degrees. This movement displaces each of the racks 40, 41, 42 and 43 in the direction of the arrow 33, due to the interengagement of the pinion 48, and also displaces the main rack bar 26 in the direction of the arrow 33. This displacement of the rack bar 26 lowers the gate arms 20 to a position of about 45 degrees. With the actuating or tripping lever 53 thus lowered to the horizontal position, the lever 54 is deflected to a position of 45 degrees, so that

25 when the train encounters the second actuating or tripping lever 54, and moves it to the horizontal position, through a distance of about 45 degrees, a further movement is imparted to each of the racks 40, 41, 42 and 43, as well as the main rack bar 26, in the direction of the arrow 33, thereby lowering the gate arms 20 to the closed or horizontal position.

30 Since the pinions 50 and 51, as will be seen from Figure 1, are positioned below the racks 42 and 43 respectively, while the pinions 48 and 49 are above the racks 40 and 41, respectively, the downward movement or the counter clockwise deflection of the actuating or tripping lever 53 and 54 in the direction of the arrow 63, will raise or deflect the actuating or setting levers 55 and 56, in a clockwise direction indicated by the arrows 64. Thus with the movement of the train of actuating racks 40, 41, 42 and 43 in the direction of the arrow 33, the lever 55 will be raised to a horizontal position, while the lever 56 will be raised to an inclined position of 45 degrees. With the second movement of the train of actuating racks, in the direction of the arrow 33, the lever 55 will be raised to an inclined position of 45 degrees, while the lever 56 will be raised to a vertical position.

35 Thus, as the train has passed the crossing and the gates, it first encounters the lever 55, in the 45 degree position, deflects the same to a horizontal position and thus reverses the movement of the train of actu-

ating racks, in the direction of the arrow 34, and thereby raises the gate arms 20 to an angle of about 45 degrees. Upon a further travel of the train it encounters the second lever 56, then in the 45 degree position, and by deflecting the same to the horizontal position imparts a further movement to the train of actuating racks, and thus raises the gate arms 20 to the vertical or full open position.

40 By the provision of my novel successive series of actuating, setting or tripping devices, both in advance and beyond the gate, a gradual closing and opening of the gates may be effected. Moreover, by the provision of the resilient spring connection 16, between the lifting racks 12 and the hinged plates 5 and 6, the movement of the system is cushioned.

45 It will now be apparent that we have devised a new and useful construction in an automatic gate for railway crossings, which embodies the features of advantage enumerated as desirable in the statement of the invention and the above description, and while we have, in the present instance shown and described preferred embodiments thereof, which will give in practice satisfactory and reliable results, it is to be understood that such embodiments are susceptible of modification in various particulars without departing from the scope of the invention or sacrificing any of its advantages.

50 Having thus described our invention, what we claim as new and desire to secure by Letters Patent is:—

55 1. In a device of the character stated, a rail, a pivotally mounted gate arm, a lifting rack operatively engaging the same, a main operating shaft extending transversely of said rail, a lifting pinion carried by said main operating shaft in mesh with said lifting rack, a main operating rack, an operating pinion carried by said main operating shaft in mesh with said main operating rack, a train operated gate actuating device, spaced a suitable distance from said gate arm, in advance thereof, comprising an actuating lever positioned adjacent to said rail, an actuating pinion connected to said actuating lever, an actuating rack in mesh with said actuating pinion and connecting means intermediate said actuating rack and said main operating rack.

60 2. In a device of the character stated, a rail, a pivotally mounted gate arm, an upright lifting rack operatively engaging the same, a main operating shaft extending transversely of said rail, a lifting pinion carried by said main operating shaft in mesh with said lifting rack, a main operating rack extending longitudinally of said rail, an operating pinion carried by said operating shaft, in mesh with said main operating rack, a pair of corresponding train

operated gate actuating devices, spaced a suitable distance from said gate arm, on either side thereof, each comprising an actuating lever positioned adjacent to said rail, an actuating pinion carried by said actuating lever, a horizontal actuating rack in mesh with said actuating pinion, and connecting means intermediate each of said actuating racks and the corresponding terminals of said main operating rack.

3. In a device of the character stated, a rail, a pivotally mounted gate arm, a vertical lifting rack operatively engaging the same, a horizontal main operating shaft extending transversely of the rail, a lifting pinion carried thereby in mesh with said lifting rack, a main operating rack, an operating pinion carried by said operating shaft in mesh with said main rack, a plurality of successive train operated gate actuating devices, spaced from said main rack at suitable distances in advance thereof, each including an actuating rack operatively connected with each other and with said main rack, actuating pinions in mesh with said actuating racks, and actuating arms carried by said actuating pinions in successive angular positions with respect to each other, whereby the successive deflections of said actuating arms will successively deflect the gate arm by suitable increments from the open to the closed position thereof.

4. In a device of the character stated, a rail, a pivotally mounted gate arm, a lifting

rack operatively engaging the same, a horizontal main operating shaft extending transversely of the rail, a lifting pinion carried thereby in mesh with said lifting rack, a main rack, a pinion carried by said operating shaft in mesh with said main rack, a plurality of successive train operated gate actuating devices spaced from said rack at suitable distances in advance thereof, each including an actuating arm operatively connected with each other and with said main rack, actuating pinions in mesh with said actuating racks, and actuating arms carried by said actuating pinions in successive angular positions with respect to each other, whereby the successive deflections of said actuating arms will successively deflect the gate arm by suitable increments from the open to the closed position thereof, a plurality of successive train operated gate actuating devices spaced suitable distances from said main rack, past the gate, each comprising an actuating rack operatively connected with the same and with each other, actuating pinions in mesh with said actuating racks, and actuating arms; each of said actuating arms being positioned in successive angular relation to each other, whereby the gate arm may be deflected by suitable successive increments from the closed to the open position thereof, by the successive deflection of said actuating arms.
